Primary Examiner — Robert M Spear*Assistant Examiner* — Ryan Harvey*(74) Attorney, Agent, or Firm* — Baker & Hostetler LLP(57) **CLAIM**

I claim the ornamental design for a plyometric box comprising three different heights, as shown and described.

DESCRIPTION

FIG. 1 is a perspective view of a plyometric box comprising three different heights showing our new design.

FIG. 2 is a front view thereof;

FIG. 3 is a rear view thereof;

FIG. 4 is a side view thereof;

FIG. 5 is an opposite side view thereof;

FIG. 6 is a top view thereof; and,

FIG. 7 is a bottom view thereof.

The broken lines illustrate portions of the article that form no part of the claimed design.
